UNITED STATES PATENT OFFICE.

EARL G. WATROUS, OF CHICAGO, ILLINOIS.

WATER-CLOSET.

No. 901,572.

Specification of Letters Patent.

Patented Oct. 20, 1908.

Application filed July 21, 1902. Serial No. 116,458.

To all whom it may concern:

Be it known that I, EARL G. WATROUS, a citizen of the United States, residing at Chicago, in the county of Cook and State of Illinois, have invented a certain new and useful Improvement in Water-Closets, of which the following is a description, reference being had to the accompanying drawings, forming part of this specification.

My invention has been designed primarily for use in connection with the water closets in railroad cars and similar places, and is especially adapted thereto; but it may also be utilized in house closets and other places, as hereafter explained.

In the accompanying drawings Figure 1 is a vertical sectional view of a closet and its coöperating valves embodying my invention, and Fig. 2 a detail top plan view, partly in section, approximately on the line 2—2 of Fig. 1.

The same letters of reference are used to indicate corresponding parts in both views.

The closet proper is composed of the bowl A supported by the base B and surrounded at its top with the flushing rim C discharging into the bowl A by the usual jet openings a, and a vertical tubular chamber D in rear of the bowl A, extending from top to bottom of the closet and communicating with the bottom of the bowl A by the discharge opening b. This discharge opening, or its communication with the lower end of the chamber D, is controlled by a valve E which seats upon the flaring upper end of a discharge pipe or tail piece F inserted in the lower end of the chamber D. The flaring upper end e of said discharge pipe, which constitutes a seat for the valve E, is supported (with interposed packing) upon an internal annular shoulder d upon the wall of the chamber D, and beneath the base of the closet the pipe F is provided with external threads upon which is screwed a nut G which bears against the under side of the base of the closet and serves to hold the discharge pipe F firmly in position.

The valve E is of hollow cylindrical form and is provided with a vertically extending tubular stem H which communicates with the interior of the valve E, and through the central opening e in the bottom of the latter with the discharge pipe F. Screwed upon the upper end of the tubular valve stem H is a casting I having upon its upper side a loop or bail J into which projects the for-

ward end of a lever K which is fulcrumed at its rear side at L. Secured to the outer side of the casting I, and depending therefrom around the tubular valve stem H is a sleeve M, which forms an annular chamber around the valve stem, open at its lower and closed at its upper end. The tubular valve stem H is provided with an overflow opening N, which prevents the water rising in the closet bowl beyond the level indicated by the dotted line and the portion of the annular chamber formed by the depending sleeve M, beneath the overflow opening N, constitutes a trap between the interior of the valve stem, valve and discharge pipe, and the interior of the chamber D and closet bowl A.

As will be understood from the foregoing description, when the valve E is lifted from its seat, by means of the lever K or otherwise, the contents of the closet bowl will discharge through the opening b and discharge pipe F, and when the valve is seated again and water admitted to the closet bowl it may rise therein to the level of the overflow opening N.

The valve stem is guided in its vertical movements by a guide bridge O, of irregular form but approximately circular in cross section, secured in the upper end of the chamber D and provided with a central opening in which the sleeve M surrounding the valve stem fits and slides in the vertical movement of the latter. In the present instance this guide bridge O is secured in place in the upper end of chamber D by means of an arm P projecting from its upper forward side and engaging the under surface of the top of the flushing rim C of the closet, and by a screw Q engaging a threaded hole in the lower rear side of the bridge O and provided with a large head whose under side projects over and engages the upper surface of the rear wall of the chamber D of the closet. By turning this screw in a direction to cause it to enter further into the bridge O, while its head is engaged with the upper surface of the wall of the chamber D, the bridge O will be forced upward and its arm P held in firm engagement with the under surface of the top of the flushing rim, and the bridge thereby secured in position by the screw Q.

Mounted upon the upper rear side of the closet, and covering the top of the chamber D and the supplemental chamber D' project-

ing rearwardly therefrom and communicating therewith, is a metal plate R whose shape in cross section is shown in Fig. 1 and in plan view in Fig. 2. This plate R is provided with an integral tubular extension S depending from it into the supplemental chamber D' of the closet structure, while projecting upward from the plate R, coincident with said tubular depending extension, is an exteriorly threaded pipe connection T. The plate R is secured to the closet structure, first, by the seat posts U which pass downward through the opposite sides of the plate, Fig. 2, and through the outwardly projecting portions of the closet and have nuts secured upon their lower ends, and second, by a flanged nut V extending upwardly through a central opening in the bottom of the supplemental chamber D' of the structure and screwed into the internally threaded lower end of the tubular extension S depending from the plate R. The seat posts U therefore serve to firmly secure the forward portion of the plate R to the closet, while the nut V clamps the rear portion of it thereto, suitable packing f being interposed around the joint of the plate R with the top of the closet and between the flange of the nut V and the bottom of the supplemental chamber D' thereof.

The seat W and lid X of the closet are hinged to the seat posts U in the usual manner.

Suitably coupled to the pipe connection T of the plate R is a slow-closing water closet valve Y of suitable construction for the purposes hereafter explained. In the present instance I have selected for purposes of illustration the valve which I actually employ in practice, and which is illustrated and described in detail in my prior patent No. 710,128, dated September 30, 1902, to which application reference may be made for a more particular description of the details of such valve than may be here given. It will suffice to here say that the valve contains an inlet chamber A' to which the water supply under pressure is constantly admitted from a pipe connected to the valve by the pipe connection B' at the rear side of the latter; a discharge chamber C' beneath the inlet chamber A' and separated therefrom by the main valve E'; a cushioning chamber F' immediately above the inlet chamber A' and separated therefrom by a check valve G'; and a retarding chamber H' above the cushioning chamber F' and separated therefrom by the piston I'. The piston I' is connected with the main valve E' by a tubular stem J', to whose upper end the piston I' is secured and upon whose exterior beneath the piston the check valve G' has its bearing and vertical movement.

Extending vertically through the tubular

valve stem J' is a rod K' whose upper end has screwed upon it a nut L' which co-operates as a relief valve with the upper end of the tubular valve stem J' as hereafter explained. Beneath the lower end of the tubular valve stem J' the rod K' has secured upon or formed integral with it a block or casting M', with a recess in the side of which is engaged an arm N' projecting from a rockshaft O' journaled in the valve casing. This rock-shaft projects through the valve casing, to the exterior thereof, and has secured upon it a handle or lever (not shown) by which it may be rocked, in the manner usual in valves of this character, to lift the rod K' and valve stem and main valve. When the rod K' is so lifted it will rise slightly before the block M' carried by it contacts with the lower end of the valve stem J' and begins to lift the latter and the main valve. This independent upward movement of the rod K' serves to lift the valve L' carried by the upper end of the rod from its seat, and thereby establish free communication between the retarding chamber H' and the discharge chamber C', so that the water in the former chamber may readily escape to the latter chamber as the piston I' is thereafter lifted with the main valve, it being understood that the upper end of the block M' does not fit tightly enough against the lower end of the valve stem J' to prevent the escape of water therefrom. The opening of the main valve E' by such lifting of the rod K' will lift the piston I' in the retarding chamber H', the water above the piston escaping downward through the tubular valve stem in the manner explained, while the enlarged space or chamber F' beneath the piston becomes filled with water which enters it from the inlet chamber A', past the check valve G' which rises from its seat for such purpose. When the handle by which the main valve has thus been lifted from its seat is then released, the rod K' instantly drops downward until the valve L' at its upper end seats itself and cuts off communication between the retarding chamber H' and discharge chamber C', and as the main valve and connected parts thereof descend their movement is opposed by the water beneath the piston I' in the cushioning chamber F', and by the partial vacuum which the downward movement of the piston tends to create in the retarding chamber H' above it. A suitable by-pass shown and described in my patent heretofore referred to is provided, connecting the chambers F' and H' with each other, through or around the piston I', and the piston and main valve can descend only as fast as water can pass from the chamber F' to the chamber H through such by-pass. This retards the closing movement of the main valve and permits the water to flow from the inlet chamber

and supply pipe into and through the discharge chamber of the valve, and thence to the closet bowl, while the main valve is closing. In my present invention I connect this slow-closing inlet valve with the discharge valve controlling the discharge from the closet bowl in such manner that the opening of the inlet valve, by means of the handle or lever referred to, will also open the discharge valve, permitting the contents of the closet bowl to discharge and the closet to be flushed by the water admitted by the inlet valve; and the coöperation of the two valves is further such that upon the release of the operating handle or lever and return movement of the parts the discharge valve will seat itself and cut off the discharge from the closet bowl before the inlet valve seats itself and entirely cuts off the water supply, so that after the discharge valve has been seated a sufficient amount of water will be admitted to the closet bowl to refill the same. To this end the rod K' or the casting M' secured to its lower end is provided with a depending extension K'' which extends downward through the depending tubular extension of the plate R of the closet, into the supplemental chamber D' thereof, and passes between the forked rear ends of the lever K, as shown in Fig. 2.

Beneath the lever K the rod K'' has screwed upon it a nut P' having a round or conical upper end adapted to coöperate with a correspondingly shaped seat formed in the under side of the forked rear end of the lever K. The nut P' may be adjusted up or down upon the rod K'', so as to time the closing of the discharge and inlet valves relatively to each other as desired, and the nut P' may be then locked in adjusted position by a lock nut Q' screwed into its lower end and engaging the lower end of the rod K''. Under this construction and arrangement of the parts, when the operating handle or lever of the inlet valve is lifted in the usual manner, to open said valve, the discharge valve at the bottom of the closet bowl is also opened, and the contents of the closet discharge and the water admitted by the inlet valve flushes the closet. Upon then releasing the handle the inlet valve slowly closes, and controls the closing movement of the discharge valve, but the latter valve reaches its seat first and cuts off the escape of water from the closet bowl in time to permit the proper refilling of the latter before the inlet valve reaches its seat.

While the water for flushing the closet bowl passes across the top of the chamber D, above the guide bridge O, and enters the bowl through the flushing rim C, it is not essential, or even desirable, that the bridge O shall so closely fit the walls of the chamber D as to permit no water to escape

around it and pass downward through the chamber D, since a small amount of water passing downward over the walls of the chamber D at each flushing operation will serve to cleanse said walls.

The structure above described is complete for use in railroad cars and like situations, where there is no sewer gas to be guarded against; but where the closet is used in houses and other situations where sewer gas is present a suitable trap will be interposed in the pipe connecting the tail-piece or discharge pipe F with the pipe leading to the sewer.

Having thus fully described my invention, I claim:

1. In a water closet, the combination of a discharge valve controlling the discharge from the closet bowl, and a quick opening inlet valve permitting an unobstructed flow at the limit of its movement in one direction when the valve is opened and having a retarded movement in the other direction whereby the valve is closed gradually, a connection between said valves, and manually operable means whereby said valves may be positively opened, the closing movement of the inlet valve serving to also control the closing movement of the discharge valve.

2. In a water closet, the combination of a discharge valve controlling the discharge from the closet bowl, and a quick opening inlet valve permitting an unobstructed flow at the limit of its movement in one direction when the valve is opened and having a retarded movement in the other direction whereby the valve is closed gradually, a connection between said valves whereby the opening and closing movements of the inlet valve serve to control the opening and closing movements, respectively, of the discharge valve, and manually operable means for positively operating the connection to open the valves.

3. In a water closet, the combination of a discharge valve controlling the discharge from the closet bowl, and a quick opening inlet valve permitting an unobstructed flow at the limit of its movement in one direction when the valve is opened, and having a retarded movement in the other direction whereby the valve is closed gradually, said opening movement of the inlet valve serving to positively open the discharge valve, and said closing movement of the inlet valve serving to retard the closing movement of the discharge valve, but permitting the former to close independently of the latter.

4. In a water closet, the combination of a discharge valve controlling the discharge from the closet bowl, and a quick opening inlet valve permitting an unobstructed flow at the limit of its movement in one direction when the valve is opened, and having a retarded movement in the other direction

whereby the valve is closed gradually, said closing movement of the inlet valve serving to retard the movement of the discharge valve until the latter is seated and said inlet valve having further independent movement before being seated, whereby the closet bowl is refilled by the final flow of water through the inlet valve.

5. In a water closet, the combination of a discharge valve controlling the discharge from the closet bowl, a quick opening inlet valve permitting an unobstructed flow at the limit of its movement in one direction when the valve is opened, and having a retarded movement in the other direction whereby the valve is closed gradually, and an adjustable connection between said valves whereby the opening movement of the inlet valve serves to positively open the discharge valve and whereby the closing movement of the discharge valve may be completed in advance of the closing of the inlet valve to any desired degree.

6. In a water closet, the combination of a discharge valve controlling the discharge from the closet bowl, a quick-opening inlet valve permitting an unobstructed flow at the limit of its movement in one direction when the valve is opened, and having a retarded movement in the other direction whereby the valve is closed gradually, and a slotted connection between said valves whereby after said discharge valve is seated said inlet valve has slight independent further movement to permit the closet bowl to be refilled by the final flow of water through the inlet valve.

7. In a water closet, a closet structure comprising a bowl provided with a flushing rim and an integral vertical chamber in rear of said bowl and connected with the bottom thereof by a discharge opening, and a water supply passage transverse of and above the upper end of the vertical chamber and communicating with the flushing rim, in combination with a discharge valve seated in said chamber beneath said discharge opening, a slow-closing inlet valve controlling the supply of water for flushing the closet bowl, and an adjustable connection between said inlet and discharge valves whereby opening of the inlet valve serves to open the discharge valve and the closing of the discharge valve is controlled by the closing movement of the inlet valve and whereby the closing of said valves relatively to each other may be timed as desired; substantially as described.

8. In a water closet, a closet structure comprising a bowl provided with a flushing rim and a vertical chamber in rear of said bowl and connected with the bottom thereof by a discharge opening, in combination with a discharge valve located in said chamber beneath the discharge opening from the closet bowl and having a depending rod or

bowl and provided with a stem extending upward through said chamber, a slow-closing inlet valve mounted above and at one side of said chamber and controlling the supply of water for flushing the closet, and a connection between said inlet valve and the stem of the discharge valve by which the opening of the inlet valve serves to open the discharge valve and the closing movement of the inlet valve serves to control without being controlled by the closing of the discharge valve; substantially as described.

9. In a water closet, a closet structure comprising a bowl provided with a flushing rim and a vertical chamber in rear of said bowl and connected with the bottom thereof by a discharge opening and a transverse water supply passage above the upper end of said chamber, in combination with a discharge valve located in said chamber beneath the discharge opening from the closet bowl and provided with a stem extending upward through said chamber, a slow-closing inlet valve mounted above said chamber and controlling the supply of water for flushing the closet, and an adjustable connection between said inlet valve and the upper end of the stem of the discharge valve whereby the opening movement of the inlet valve opens the discharge valve and the closing movement of the inlet valve controls the closing of the discharge valve, and whereby the closing movements of said valves relatively to each other may be timed as desired; substantially as described.

10. In a water closet, a closet structure comprising a bowl provided with a flushing rim and a vertical chamber in rear of said bowl and connected with the bottom thereof by a discharge opening, in combination with a discharge valve located in said chamber beneath the discharge opening from the closet bowl and provided with a stem extending upward through said chamber, a slow-closing inlet valve mounted above said chamber and provided with a depending stem or rod, and a lever connecting said depending rod with the vertically extended stem of the discharge valve, whereby the opening of the inlet valve serves to open the discharge valve and whereby the closing of the discharge valve is controlled by the closing movement of the inlet valve; substantially as described.

11. In a water closet, a closet structure comprising a bowl provided with a flushing rim and a vertical chamber in rear of said bowl and connected with the bottom thereof by a discharge opening, in combination with a discharge valve located in said chamber beneath the discharge opening from the closet bowl and provided with a stem extending upward through said chamber, a slow-closing inlet valve mounted above said chamber and having a depending rod or

stem, and a lever having an adjustable connection with said depending rod and also connected with the vertically extending stem of the discharge valve, whereby the opening 5 of the inlet valve serves to open the discharge valve and the closing movement of the inlet valve serves to control the closing movement of the discharge valve and whereby the closing movements of said valves relatively to each other may be timed as desired; 10 substantially as described.

12. In a water closet, the combination of a discharge valve controlling the discharge from the closet bowl, a slow-closing inlet 15 valve controlling the supply of water for flushing the bowl and provided with an operating rod, a nut screwing onto the end of such rod, and a pivoted lever arranged in the path of said nut and operatively connected 20 to the discharge valve; substantially as described.

13. In a water closet, the combination of a discharge valve controlling the discharge from the closet bowl, a slow-closing inlet 25 valve controlling the supply of water for flushing the bowl and provided with an operating rod, a nut screwing onto the end of such rod, and a lever pivoted at one end at one side of said rod and arranged in the 30 path of said nut, the other end of such lever being operatively connected to the discharge valve; substantially as described.

14. In a water closet, the combination of a discharge valve controlling the discharge 35 from the closet bowl, a slow-closing inlet valve controlling the supply of water for flushing the bowl and provided with an operating rod, a nut screwing onto the end of such rod, a pivoted lever actuated by said 40 nut and operatively connected to the discharge valve, and means for locking said nut on the said rod; substantially as described.

15. In a water closet, the combination of a discharge valve controlling the discharge 45 from the closet bowl, an inlet valve device for controlling the supply of water for flushing the bowl, a plate R arranged on the closet structure and supporting the inlet valve device, said plate having an extension S, an operating rod for the inlet valve, and a lever pivoted on said extension and actuated by said rod, said lever being operatively connected to the discharge valve; substantially 55 as described.

16. In a water closet, the combination with the closet structure having a rear chamber D', of a discharge valve controlling the discharge from the closet bowl, a plate R arranged on the closet structure and having an extension S within the chamber D', an inlet valve device supported by said plate and having an operating rod or stem projecting into said extension, a lever K pivoted on the 60 extension and operatively connected to the 65

discharge valve, and an adjustable projection on the rod or stem for actuating said lever; substantially as described.

17. In a water closet having a bowl provided with a rearwardly disposed integral 70 vertical chamber, the combination with a quick-opening and slow-closing inlet valve permitting an unobstructed flow at the limit of its movement in one direction when the valve is opened, and having a retarded movement in the other direction whereby the valve is closed gradually, of a vertically movable discharge valve located in said vertical chamber and opened by the opening movement of the said inlet valve, and arranged to close 80 in advance of the closing of said inlet, said discharge valve carrying a trapped overflow device for preventing overflow of the bowl. 75

18. In a water closet, the combination of an inlet valve device for controlling the 85 supply of water for flushing the bowl, a discharge valve operated by the inlet valve for controlling the discharge from the bowl and comprising a valve body having an opening through itself to the discharge, a hollow 90 stem on said valve body and communicating with said opening, said stem having an overflow opening, an outer depending sleeve M around said stem, and an operating connection actuated by the inlet valve and engaging 95 said valve stem; substantially as described.

19. In a water closet, the combination of an inlet valve device for controlling the supply of water for flushing the bowl, a discharge valve operated by the inlet valve for controlling the discharge from the bowl and comprising a valve body having an opening through itself to the discharge, a hollow 100 stem on said valve body and communicating with said opening, said stem having an overflow opening, a cap or head piece I secured to the upper end of the valve stem, an outer depending sleeve M also secured to such head piece, and an operating connection actuated 110 by the inlet valve and engaging said head piece; substantially as described.

20. The combination, with the closet structure and bowl having a discharge or outlet b, of a hollow discharge valve E controlling 115 said outlet and having a bottom opening e, a hollow valve stem H on the valve and communicating with its interior and its opening e, said stem having an overflow opening N, an inlet valve device, and a pivoted lever K actuated by said inlet valve device and engaging the said valve stem to operate the discharge valve; substantially 120 as described.

21. The combination, with the closet structure and bowl having a discharge or outlet b, of a hollow discharge valve E controlling 125 said outlet and having a bottom opening e, a hollow valve stem H on the valve and communicating with its interior and its opening 130

e, said stem having an overflow opening N, a sleeve M surrounding the valve stem for a portion of its length a head piece I secured to the upper ends of the stem and sleeve, an 5 inlet valve device, and a pivoted lever K actuated by said inlet valve device and engaging the said head piece to operate the discharge valve; substantially as described.

22. In a water closet, the herein described 10 closet structure comprising the bowl A, base B, flushing rim C and a partition forming a vertical chamber D in rear of bowl A and communicating with the bottom thereof by the opening b, all formed of a single integral 15 piece of earthenware, said chamber D having a partition o forming a water supply chamber and passage thereabove; substantially as described.

23. In a water closet, the herein described 20 closet structure comprising the bowl A, base B, flushing rim C, vertical chamber D, and supplemental chamber D', all formed of a single integral piece of earthenware, said vertical chamber D having a partition o 25 forming a water supply chamber thereabove communicating with said supplemental chamber D'; substantially as described.

24. In a water closet, the closet structure comprising the bowl A, base B, flushing rim 30 C and vertical chamber D in rear of the bowl A and communicating with the bottom thereof by the opening b, said structure being composed of a single integral piece of earthenware, in combination with the discharge 35 valve E seating in the chamber D beneath the opening b and provided with a vertically extending stem, the bridge-piece O secured in the top of the chamber D and serving to close the same and to form a guide for the 40 upper end of the valve stem, a plate R secured to the top of the closet structure above the chamber D, a slow closing inlet valve carried by the plate R, and a connection between said valve and the stem of the 45 discharge valve above the bridge-piece O; substantially as described.

25. In a water closet, the closet structure comprising the bowl A, base B, flushing rim C and vertical chamber D in rear of the bowl 50 A and communicating with the bottom thereof by the opening b, all formed of a single integral piece of earthenware, in combination with the tail-piece or discharge pipe F having a flaring upper end c seating against 55 an internal annular shoulder d in the chamber D below the discharge opening b and forming a valve seat, the nut G screwed upon the tail-piece F beneath the closet structure and bearing against the bottom of 60 the same, the discharge valve E seating against the valve seat c formed by the flaring upper end of the tail-piece F, the plate O closing the upper end of the chamber D, and the valve stem extending upwardly from

the valve E through said plate O; substantially as described. 65

26. In a water closet, the closet structure comprising the bowl A, base B, flushing rim C and vertical chamber D in rear of the bowl A and communicating with the bottom thereof by the opening b, in combination with the tail-piece F having a flaring upper end c seating against an internal annular shoulder d formed on the interior of the chamber D beneath the opening b, the 70 nut G screwed upon the tail-piece F beneath the closet structure and bearing against the bottom of the same, the discharge valve comprising the cylindrical shell E open at its upper and lower ends, the clamping nut 75 e screwed into the lower end of the valve shell and clamping between itself and the shell the rubber ring seating against the valve seat c, the plate O closing the upper end of the chamber D, and the operating rod 80 or stem extending vertically from the valve E through said plate; substantially as described.

27. In a water closet, a closet structure comprising the bowl A, base B, flushing rim C 90 and vertical chamber D in rear of the bowl A and communicating with the bottom of the latter by the opening b, all composed of a single integral piece of earthenware, the valve E coöperating with the seat in the 95 chamber D beneath the opening b, the plate O secured in the upper end of the chamber D by the flange screw Q and the arm P, and the operating rod or stem extending upward from the valve E through the plate O; substantially as described. 100

28. In a water closet, the closet structure comprising the bowl A, base B, flushing rim C and vertical chamber D in rear of the bowl A and communicating with the bottom 105 of the latter by the opening b, and the supplemental chamber D' at the upper rear side of the chamber D, all formed of a single integral piece of earthenware, in combination with the valve E coöperating with the 110 seat in the chamber D beneath the opening b, the plate O secured in the upper end of the chamber D, the valve rod or stem extending upward from the valve E through the plate O, the plate R covering the top 115 of the chamber D and supplemental chamber D' and provided with the depending extension S in chamber D', the flanged nut V screwed into the lower end of the extension S and bearing against the under side of the 120 chamber D', the seat posts U extending downward through the opposite sides of the plate R near its forward end, the slow-closing valve carried by the plate R above the chamber D' and having the depending 125 rod K'' extending downward into the chamber D', and the lever K connecting said rod with the upper end of the stem of the dis-

- charge valve E above the plate O; substantially as described.
29. In a water closet structure comprising the bowl and a vertical chamber connected 5 with the bottom thereof by a discharge opening, in combination with a discharge valve seated in said chamber beneath the discharge opening, a valve stem for the valve, a bridge arranged in the chamber to guide the valve 10 stem and having a flanged screw Q bearing against an upper edge of said chamber and also having an arm adapted to be pressed firmly against a portion of the closet structure to bind the bridge in place, an inlet 15 valve controlling the supply of water for flushing the closet bowl and an operating connection between the inlet valve and the said valve stem of the discharge valve; substantially as described.
- 20 30. In a water closet, a closet structure comprising a bowl, a vertical chamber in the rear thereof and connected with the bottom of the same by a discharge opening, and a supplemental chamber D' communicating 25 with the vertical chamber, a discharge valve operating in the vertical chamber for controlling the discharge from the bowl, an inlet valve controlling the supply of water for flushing the bowl, an operating rod K'' 30 therefor extending into chamber D' and an operating connection between said rod and the discharge valve and operated by said rod; substantially as described.
31. In a water closet, a closet structure 35 comprising a bowl, a vertical chamber in the rear thereof and connected with the bottom of the same by a discharge opening, and a supplemental chamber D' communicating with the vertical chamber, a discharge valve 40 operating in the vertical chamber for controlling the discharge from the bowl, a plate R arranged on the closet structure and having an extension S depending in said chamber D', an inlet valve controlling the supply 45 of water for flushing the bowl, an operating rod K'' therefor extending into chamber D' and through said extension, and a lever K pivoted on the extension and actuated by said rod and engaging the discharge valve; 50 substantially as described.
32. In a water closet, a closet structure comprising a bowl, a vertical chamber in the rear thereof and connected with the bottom of the same by a discharge opening, and a supplemental chamber D' communicating 55 with the vertical chamber, a discharge valve operating in the vertical chamber for controlling the discharge from the bowl, a plate R arranged on the closet structure and having an extension S depending in said chamber D', a nut V engaging said extension and holding the latter in place, an inlet valve 60 controlling the supply of water for flushing the bowl, an operating rod K'' therefor ex-
- tending into chamber D' and a lever K 65 pivoted on the extension and actuated by said rod and engaging the discharge valve; substantially as described.
33. In a water closet, a closet structure comprising a bowl, a vertical chamber in the rear thereof and connected with the bottom of the same by a discharge opening, and a supplemental chamber D' communicating 70 with the vertical chamber, a discharge valve operating in the vertical chamber for controlling the discharge from the bowl, a plate R arranged on the closet structure and having a tubular extension S depending in said chamber D' and a pipe connection T, an inlet valve controlling the supply of water 75 for flushing the bowl and secured to said pipe connection, an operating rod K'' therefor passing into said extension, and a lever K pivoted to said extension and actuated by the rod, said lever engaging the discharge 80 valve; substantially as described.
34. In a water closet, a closet structure comprising a bowl, a vertical chamber in the rear thereof and connected with the bottom of the same by a discharge opening, and a supplemental chamber D' communicating 85 with the vertical chamber, a discharge valve operating in the vertical chamber for controlling the discharge from the bowl, a plate R arranged on the closet structure, and having an extension S depending in chamber D', a hollow nut V engaging said extension, an inlet valve controlling the supply of water 90 for flushing the bowl, an operating rod K'' therefor passing through said extension and 95 guided as to its lower end by said hollow nut, a lever K actuated by the rod and operatively connected to the discharge valve; substantially as described.
35. In a water closet, a closet structure 100 comprising a bowl, a vertical chamber in the rear thereof and connected with the bottom of the same by a discharge opening, and a supplemental chamber D' communicating 105 with the vertical chamber, a discharge valve operating in the vertical chamber for controlling the discharge from the bowl, a plate R arranged on the closet structure and having an extension S depending in chamber D', a hollow nut V engaging said extension, an 110 inlet valve controlling the supply of water for flushing the bowl, an operating rod K'' therefor passing through said extension, a nut P' screwing on the lower end of the rod and received by the hollow nut, and a lever 115 K adapted to be contacted and actuated by said nut P', said lever being operatively connected to the discharge valve; substantially 120 as described.
